Primary Examiner — Eric Goodman(74) *Attorney, Agent, or Firm* — Pamela L. Stewart**CLAIM**

The ornamental design for a dental syringe, as shown and described.

DESCRIPTION

FIG. 1 is a perspective view showing the new design for a dental syringe;

FIG. 2 is a side view thereof;

FIG. 3 is a top view thereof;

FIG. 4 is a bottom view thereof;

FIG. 5 is a front view thereof; and,

FIG. 6 is a back view thereof.

The broken line showing is included for the purpose of illustrating environment and forms no part of the claimed design. The drawing is lined for color.
